[57] CLAIM

The ornamental design for an radio or similar article, as shown and described.

DESCRIPTION

FIG. 1 is a top, front and left side perspective view of a radio or similar article showing my new design;

FIG. 2 is a right side elevational view of the left element thereof;

FIG. 3 is a right side elevational view of the right element thereof;

FIG. 4 is a left side elevational view of the left element thereof;

FIG. 5 is a bottom plan view thereof; and,

FIG. 6 is a rear elevational view thereof.

The cord is broken away in the drawings for ease of illustration.

FIG. 3

FIG. 5

FIG. 6
